METHOD OF MAKING MECHANICAL
OVERLAYS

Alfred E. Farley, Chicago, Ill.

Application December 6, 1948, Serial No. 63,669

18 Claims. (Cl. 101—401.3)

1

This invention relates to a novel overlay for use in printing apparatus and to a process for making the same.

A major problem that confronts the printing industry relates to the process of "making ready" the impression surface of printing apparatus. Costly and time consuming hand methods ordinarily are employed in this operation because the mechanical and chemical methods that have thus far been proposed have proven to be unsatisfactory from one standpoint or another. The importance of this problem can be seen when reference is had to the steps that ordinarily are taken to prepare for printing when using a cylinder press, i. e., a printing apparatus wherein an inked flat type form is passed under an impression cylinder that carries the paper or other material to be printed. One of the first operations is to prepare the impression surface by covering it with a number of sheets of suitable paper. The form of type that has been set up previously is locked in the bed and an impression is then pulled on a sheet of paper. Invariably this first pull shows irregularities in the printing; some parts of the printing being so weak that they are unreadable and others being so heavy that the sheet of paper is nearly cut through. The rectification of these inequalities, which are caused by variations in the heights of the type, requires great skill and experience on the part of the operator, for unless the work is done with ability and understanding, the printed sheets will appear patchy and difficult to read.

The process of correcting for the variations in the heights of the type, said variations ranging from about 0.0005 inch to about 0.005 inch, is called "making ready." It is not unusual for a large form of type to take two or three days to make ready. Conventional practice involves pulling an impression on a thin sheet of paper, cutting out with a sharp instrument those parts of the paper where the printing is too heavy, and pasting bits of tissue paper on those parts of the sheet where the printing is too light. Alternatively, the heavy parts are not cut out, but layers of tissue are pasted onto the sheet where the impressions are weak. When the sheet is completed, it is placed on the impression surface in a position corresponding exactly with that part of the form which requires the particular treatment. Another impression is then pulled and the work of cutting out and patching up is continued until the impression presents an even and regular appearance.

2

Numerous attempts have been made to develop simpler and less time consuming methods of making ready. However, the methods that have been proposed, such as chalking, etching, and the like, are far from simple, usually calling for a considerable number of steps to complete the overlay and frequently involving relatively expensive chemical treatments, the use of special inks, and the like. Ordinarily, several trial impressions or proofs must be made and the overlay set up and removed from the impression surface several times before it is finished.

It is an object of this invention to provide an accurate and effective overlay for printing.

It is another object of this invention to provide means for compensating for differences in type height in printing by a relatively simple and inexpensive process involving a single impression of an uninked printing form.

It is a further object of one embodiment of the present invention to prepare an overlay directly on the tympan roll by a rapid process which eliminates the necessity for removing the overlay for processing thereof, thereby insuring substantially perfect register.

Still another object of this invention is to prepare an overlay for printing by a single contacting of the type form with means associated with the tympan roll and adapted to receive and retain impressions.

Briefly stated, my invention comprises (1) methods of forming an overlay directly on the platen or impression cylinder of a printing machine by a single impression of the type form, and (2) new articles of manufacture—to wit, the overlays so formed. The impression member of the printing apparatus is prepared by placing thereon means for receiving and retaining an impression. The type form is then brought to bear on the assembly and an impression of the type is formed on said means. If necessary, the means is caused to harden or congeal in order to permanently retain the impression. The means is now low where the type is high and high where the type is low and is in direct and perfect register with the type. A suitable top sheet or sheets may then be placed over said means and the apparatus is then ready for printing. Although special inks and the like may be used, they are not essential.

In order that my invention may be more fully disclosed, reference is had to the accompanying drawings which illustrate several forms of impression receiving and retaining means which may be employed in the practice of my invention.

and which embody the foregoing and such other principles, advantages or capabilities as may be pointed out as this description proceeds, or as are inherent in the present invention. For purposes of clarity in exposition, the following description is explicit, and the accompanying drawings are detailed, but it is distinctly to be understood that said exposition is illustrative only, and that my invention is not restricted to the particular details recited in the specification or shown in the drawings.

In the drawings:

Figures 1-4 are elevational views taken in cross-section through a form of type and a printing roll, and illustrate successive steps whereby one embodiment of my novel mechanical overlay is made ready;

Figures 5-7 are elevational cross-sectional views illustrating successive steps involved in the manufacture of another embodiment of my invention; and

Figures 8-10 are elevational cross-sectional views illustrating the appearance of a third embodiment of my invention, following successive steps in its manufacture.

Like reference characters designate like parts in the drawings and in the description thereof which follows:

Referring now in detail to the drawings, Figure 1 shows an assembly or composite 15 that I have found to be especially well suited for practicing my invention. The assembly 15 is made up of special sheets or layers and is adapted to be secured to the impression cylinder or roll 20 of a printing machine. The first layer of the assembly 15 consists of a base sheet 21 which may have a cellophane surface on that side facing the roll 20 and a tacky and/or pressure sensitive adhesive 22 on the other side thereof. By the term "adhesive," as used throughout the specification and appended claims, is meant any sticky material capable of holding powder pressed against it, and includes such diverse substances as heavy viscous inks, on the one hand, and the commercial mastic used to cement tile, on the other. A screen 23, which may be formed from conventional drafting room linen, for example, is placed over the sheet 21 bearing the adhesive 22. A third sheet 24 is then placed on top of the screen 23. The third sheet 24, which may be formed from paper or the like, is coated on one side with a suitable powder or grit 25 such as for example finely divided iron, manganese, or other metallic or nonmetallic substances. The powder 25 is loosely held on the sheet 24 by means of a suitable adhesive such as starch or flour paste. For example, the powder 25 may be mixed with ordinary starch paste made with water and the resultant mixture applied to one side of the sheet 24 and allowed to dry. The result is a structure wherein the individual particles of the powder 25 are only loosely bound to the sheet 24 and to each other. This sheet 24 is placed on the screen 23 with the coated side facing the impression member 20.

The padding 26 on the cylinder ordinarily is 0.05 inch thick. Usually, I remove about 0.020 inch of the padding 26 and replace it with the assembly 15, which may be made up and placed on the roll 20 as a unit or which may be constructed directly on the roll 20.

The type form 14 lies in the customary horizontal position in the bed with the type faces up. Numeral 27 refers to a group of contiguous low type, the faces of which are in the same hori-

zontal plane. Numeral 28 refers to a similar group of high type. In place of the type groups there can of course be half-tone cuts or other printing media the faces of which may be higher or lower than adjacent printing surfaces. Groups of type are shown as being separated by spacers 29. When the type form is contacted with the roll 20 containing the assembly 15, the type faces are pressed against said assembly, forcing powder 25 through screen 23 onto adhesive 22 and/or adhesive 22 is forced through the screen 23 and into contact with the powder 25. As a result of this operation, projections 19 consisting of agglomerated powder and adhesive are formed on the base sheet 21 opposite the type faces. The faces of the group 27 of low type as well as of the group 28 of high type act as pressure points, but the faces of the high type cause a greater compression of the powder 25 and adhesive 22. When the type form is withdrawn from contact with the impression roll 20, the assembly 15 presents graduated reliefs, i. e., inequalities of the surface are formed as shown in Figure 2. The higher projections 19 are opposite the lower groups of type and the lower projections 19 are opposite the higher groups of type, while the powder 25 opposite the spacers 29 is uncompressed. The sheet 24 is then removed and the uncompressed or screened out powder 25 brushed off or otherwise removed from sheet 23. If adhesive 22 has not been forced through the screen 23, said screen may also be removed, and the resultant overlay will appear as shown in Figure 3. The agglomerated clusters of adhesive 22 and powder 25 solidify and become hard as they dry. The overlay thus produced compensates for irregularities in the heights of the type form 14 and presents a hard solid backing for all portions of the form, whether high or low. One or more sheets of paper, cloth or similar material 30 may then be placed over the overlay, as shown in Figure 4 and the apparatus is ready for printing.

Thus it can be seen that by means of the process described, an overlay can be simply and inexpensively prepared on the impression cylinder or roll 20. The overlay need not be removed from the roll 20, hence it is in perfect register with the type form 14.

A second means for receiving and retaining an impression from a type form 14 that may be employed in my process comprises a relatively porous fabric or the like containing particular types of powders loosely bound to each side thereof. The powders are of such composition that when commingled, they interact to form a stable shape-retaining resinous or plastic composition. The powder on one side of the fabric or porous member may be, for example, trioxymethylene. The powder on the other side may then consist of a mixture of oxalic acid plus a compound such as resorcinol, phenol, alkylphenols such as paratertiary butylphenol, melamine, urea, or thiourea.

A typical assembly 16 conforming to this second embodiment is shown in Figure 8 and includes a layer of fabric 31 to one side of which a layer of powdered trioxymethylene 32 is loosely bound. A mixture 33 of the powders of resorcinol and oxalic acid are carried by the fabric 31 on the other side thereof. The oxalic acid catalyzes the reaction between the other two materials. In carrying out my method, the assembly 16 is superimposed upon the padding 34 of the print-

ing roll 35, following which the type form 14 is brought to bear against the assembly. As a consequence of this application of pressure, the powder 32 and the powder mixture 33 respectively penetrate into and through the fabric 31 and intermingle with each other. When the type form 14 is withdrawn, the assembly 16 presents the appearance illustrated in Figure 9. Advantageously, the particular powders used in this example react and cure at room temperature within a few seconds forming a relatively hard resinous composition in combination with the fabric 31. The result is a rugged unitary overlay in which the resinous composition is combined with portions of the fabric 31 and fills the interstices thereof, providing a hard, tough backing for the printing process which is to follow. The unreacted powders which are screened out may be brushed or shaken off the fabric 31, leaving opposite and in register with the groups of type (e. g., groups 27 and 28) complementary projections 18, as shown in Figure 10. When using some of the other mixtures listed above, it may be necessary to use temperatures somewhat higher than normal room temperature, in order to bring about and complete the reaction between the constituents. Overlays have been prepared in this manner that are accurate to 0.00025 inch, which is sufficient for even the finest type of printing.

If the use of oxalic acid is objectionable because of the particular type of fabric used or for some other reason, a mixture of powdered trioxymethylene and a powdered alkali may be used as one component, and powdered resorcinol, phenol, urea, etc., may be used as the other. Still another alternative group of powders that may be used in my process in the manner described comprises powdered hexamethylenetetramine as one component, and powdered resorcinol, phenol, melamine, etc., as the other. Thus it can be seen that in this embodiment of my invention a number of different types of resin- or plastic-forming materials may be used with substantially equivalent results, namely, the production of sturdy, accurate, comparatively inexpensive overlays. The particular types of powdered components used will depend upon such factors as kind and characteristics of the fabric or paper used, required reaction and curing temperature and time, degree of hardness of the resinous product, etc. The proportions of the various reactants to be used and the nature of the product obtained may be varied within limits, but in general I have found that the proportions normally used in the commercial manufacture of the particular type of resin or plastic employed give satisfactory results in my process.

I have also found that overlays may be made in accordance with my invention from a single powdered substance of suitable composition, in combination with an appropriate fabric. For example, this third embodiment of my invention, shown in Figure 5, may comprise a wool fabric 36 coated with a powdered composition 37 containing polyvinyl chloride as the principal ingredient, such as the compositions sold under the trade name Geon. The type form 14 or plate is brought to bear upon the assembly 13 thus formed, compressing the composition 37 and forming a compact mass with the fabric 36 at the desired points (Figure 6). The compressed powder composition 37 adheres tenaciously to the fabric 36 and frequently is sufficiently hard and durable that further treatment is unnecessary. The uncom-

pressed composition 37 is removed by shaking or brushing following which the overlay assumes the appearance of Figure 7, viz., a surface of graduated reliefs 17 which correct for the irregularities in the heights of the various groups of types of the type form 14. With certain of the polyvinyl chloride compositions, particularly those containing a vulcanizing agent, it is necessary to subject the fabric 36 containing the compressed composition 37 to temperatures slightly above room temperature—for example 15–25° F. above room temperature—in order to obtain the desired surface and strength characteristics. Again, a mild treatment with a suitable reagent may be resorted to, to aid in curing the compressed powders.

Although the processes herein described, particularly the process illustrated in Figures 1–4, can be used to prepare overlays that compensate for irregularities in the heights of individual pieces of type, the overlays generally need not be that exact. It frequently is satisfactory if the overlay compensates generally for high and low groups of type rather than for individual type. The overlays that can be prepared on the tympan roll without removal therefrom are especially suitable for use in machines because of their perfect register with the type form.

From the foregoing, it will be apparent that I have invented an improved type of overlay that can be used with great advantage in the printing industry. The overlays herein disclosed are prepared by novel processes that are characterized by their simplicity and speed. A single impression of the type form or plate suffices to create an accurate contour on the overlay. In some cases, no other treatment is necessary; whereas in others only brushing, shaking, heating or cooling of the overlay, or the simple application of a suitable reagent thereto serves to complete the preparation of the same. My process completely eliminates the trial and error methods heretofore used in preparing overlays and dispenses with the need for highly skilled pressmen, since the processes herein disclosed may be practiced by printing operators possessing only ordinary skill.

While I have described certain preferred embodiments of my invention, it is to be understood that my invention is not limited thereto, inasmuch as various changes and modifications may be made without departing from the spirit of the invention, the scope of which is defined in the appended claims.

I claim as my invention:

1. The process of forming an overlay which comprises providing an impression member of a printing apparatus having positioned on the impression surface thereof an assembly comprising a base sheet material with an adhesive surface on one side thereof, a porous sheet material in contact with said adhesive surface, and a sheet loosely coated on one side with finely divided particles, the coated side being in contact with said porous sheet material, applying a type form containing type of different heights to said assembly to thereby cause at least some of the particles to pass through the porous sheet material and form adhered clusters with the adhesive opposite the type, and thereafter removing the coated sheet.
2. The process of forming an overlay which comprises providing an impression member of a printing apparatus having positioned on the impression surface thereof an assembly comprising a base sheet material with an adhesive surface on one side thereof, a porous sheet material in

contact with said adhesive surface, and a sheet loosely coated on one side with finely divided metal particles, the coated side being in contact with said porous sheet material, applying a type form containing type of different heights to said assembly to thereby cause at least some of the particles to pass through the porous sheet material and form adhered clusters with the adhesive opposite the type, and thereafter removing the coated sheet.

3. The process of claim 2 further characterized in that said finely divided metal particles comprise iron particles.

4. The process of forming an overlay which comprises providing an impression member of a printing apparatus having positioned on the impression surface thereof a porous sheet material having loosely adhered to one side thereof a finely divided solid material and having loosely adhered to the other side thereof another finely divided solid material capable of reacting with the first-named material to form a resin, applying a type form containing type of different heights to said porous sheet material to thereby cause at least a portion of one of the solid materials to penetrate into the porous sheet material and contact at least a portion of the other solid material, reacting said contacted portions to form a resin in adhered relation to the porous sheet material, and removing the unreacted finely divided materials.

5. The process of forming an overlay which comprises providing an impression member of a printing apparatus having positioned on the impression surface thereof a porous sheet material having loosely adhered to one side thereof a finely divided solid material comprising a component of a resin and having loosely adhered to the other side thereof another finely divided solid material comprising another component of a resin capable of reacting with the first-named component to form a resin, applying a type form containing type of different heights to said porous sheet material to thereby cause at least a portion of one of the solid materials to penetrate into the porous sheet material and contact at least a portion of the other solid material, reacting said contacted portions to form a resin in adhered relation to the porous sheet material, and removing the unreacted finely divided materials.

6. The process of forming an overlay which comprises providing an impression member of a printing apparatus having positioned on the impression surface thereof a porous sheet material having loosely adhered to one side thereof finely divided trioxymethylene and having loosely adhered to the other side thereof a finely divided solid material capable of reacting with the trioxymethylene to form a resin, applying a type form containing type of different heights to said porous sheet material to thereby cause at least a portion of the trioxymethylene to contact at least a portion of said finely divided solid material, reacting said contacted portions to form a resin in adhered relation to the porous sheet material, and removing the unreacted trioxymethylene and finely divided solid material.

7. The process of claim 6 further characterized in that said finely divided solid material comprises a phenolic compound capable of reacting with trioxymethylene to form a resin.

8. The process of claim 6 further characterized in that said finely divided solid material comprises resorcinol.

9. The process of claim 6 further characterized in that said finely divided solid material is a member of the group consisting of urea and thiourea.

5 10. The process of forming an overlay which comprises providing an impression member of a printing apparatus having positioned on the impression surface thereof a porous sheet material having loosely adhered to one side thereof finely divided hexamethylene tetramine and having loosely adhered to the other side thereof a finely divided solid material capable of reacting with the hexamethylene tetramine to form a resin, applying a type form containing type of different heights to said porous sheet material to thereby cause at least a portion of the hexamethylene tetramine to contact at least a portion of said finely divided solid material, reacting said contacted portions to form a resin in adhered relation to the porous sheet material, and removing the unreacted hexamethylene tetramine and finely divided solid material.

15 20 25 11. The process of claim 10 further characterized in that said finely divided solid material comprises a phenolic compound capable of reacting with hexamethylene tetramine to form a resin.

30 12. The process of claim 10 further characterized in that said finely divided solid material comprises resorcinol.

13. The process of claim 10 further characterized in that said finely divided solid material is a member of the group consisting of urea and thiourea.

35 40 45 14. The process of forming an overlay which comprises providing an impression member of a printing apparatus having positioned on the impression surface thereof a porous sheet material having loosely adhered thereto a finely divided solid compressible material capable of being transformed to a hard resinous structure, applying a type form containing type of different heights to said porous sheet material to create an impression thereon by compressing at least a portion of said powder, and fixing the impression by transforming the powder to a hard resinous structure.

50 55 60 15. The process of forming an overlay which comprises providing an impression member of a printing apparatus having positioned on the impression surface thereof an assembly comprising a porous sheet material having loosely adhered thereto a finely divided compressible material capable of being or becoming hardened, applying to said assembly a type form containing types of different height and spacers, to compact said material opposite said types into a reverse image of said type form, and thereafter removing the uncompacted material opposite said spacers.

65 70 75 16. The process of forming an overlay which comprises placing on the impression surface of a printing apparatus a sheet having loosely adhered thereto a finely divided compressible material capable of being or becoming hardened, applying to said compressible material the type form for which the overlay is to be made, said type form including high and low sections and spacers, whereby material opposite said high and low sections is compacted correspondingly and material opposite said spacers remains uncompacted, and thereafter removing the uncompacted material from said sheet.

17. The process of forming an overlay which comprises placing on a printing apparatus a

porous sheet loosely coated on one side thereof with a finely divided compressible material and having means on the other side thereof for retaining material which passes through said porous sheet, applying to said compressible material the type form for which the overlay is to be made, said type form including high and low sections and spacers, whereby material opposite said high and low sections is compacted correspondingly and material opposite said spacers remains uncompacted, and thereafter removing the uncompacted material from said sheet.

18. The process of claim 14 further characterized in that said finely divided solid compressible material comprises polyvinyl chloride.
